United States Patent Office.

FRANK W. REILLY, OF CHICAGO, ILLINOIS, ASSIGNOR TO HIMSELF, GEORGE F. ROOT, EBENEZER T. ROOT, AND CHAUNCEY M. CADEY, OF SAME PLACE.

Letters Patent No. 76,944, dated April 21, 1868.

IMPROVEMENT IN LIFTING-APPARATUS.

The Schedule referred to in these Letters Patent and making part of the same.

TO ALL WHOM IT MAY CONCERN:

Be it known that I, FRANK W. REILLY, of the city of Chicago, in the county of Cook, and State of Illinois, have invented new and useful Improvements in "Weight-Lifting Apparatus;" and I do hereby declare that the following is a full and exact description thereof, reference being had to the accompanying drawings, making part of this specification, in which—

Figure 1 represents the front view, and

Figure 2 the side view of the apparatus.

Figure 3 the plan of the weight, and

Figure 4 the plan of the spider.

Similar letters of reference in the several figures denote similar parts of the machine.

My invention consists of an improved form of apparatus designed to facilitate the practice of lifting weights, either as a gymnastic exercise or as a curative agency in the treatment of disease; and to make it clearly understood, I shall first proceed to describe the common contrivance heretofore in use in gymnasiums and elsewhere, designed for the same purpose, and shall then point out the nature of my improvements.

The apparatus heretofore in use embraces a table or platform, four feet or so in height, and about three feet square, in the centre of which is a strong iron rod, terminating in an eye at its upper extremity, and passing through the table to a point near the floor, where its lower end is firmly secured to a horizontal disk.

In lifting by this apparatus, after the desired amount of weight is deposited upon the disk, a horizontal bar is slipped through the eye of the rod, and the patient stands upon the platform or table, astride this bar, as it were, the ends of which he grasps in his hands, the height of the bar above the table having been previously so adjusted as to compel the patient to stoop slightly in grasping it, which he does by bending the knees while holding his body erect. Having taken a firm hold of the cross-bar with his hands, the patient straightens his legs, and so raises the cross-bar, rod, disk, and the weights piled thereon.

There have been various modifications in the construction of this kind of lifting-apparatus, for some of which patents have been heretofore granted by the United States Patent Office to D. P. Butler; but Mr. Butler's apparatus, like that of his predecessors, contains the general feature of a central rod projecting vertically above the platform, and involves the use of a horizontal bar, which the patient must bestride in the act of lifting, thereby assuming a position more or less inconvenient to all, and especially awkward and unpleasant in the case of ladies.

The object of my improvement is to avoid the necessity of assuming this disagreeable position while lifting, and also to enable the patient to lift in a greater variety of positions, as, for example, with the hands hanging down at the sides of the body in the most natural way.

I accomplish this result by having two vertical rods provided with suitable handles, projecting above the table, and connected with the necessary mechanism beneath the table for carrying the weights used, so that the centre of the table is without obstruction, and the patient can stand between the two rods, and having grasped the handles, can lift with the hands at the sides of the body, or can turn partly around, so as to lift with one hand in front and the other behind the body.

My apparatus consists of a substantial table, A, the legs of which are secured to a platform, B, which rests upon the floor. A smaller platform, C, rests upon springs D D, and is located in the middle of the platform B, and sustains, when the apparatus is not in use, the disk S, which is secured to the lower part of the vertical rod E, and serves to carry the weights which may be deposited upon it. The rod E terminates at its lower end in a conical point, F, which passes through corresponding openings in the platforms C and B, and is thereby guided to its proper position when the weights are being lowered.

If found necessary, the upper end of the rod E may be made to project a few inches above the cross-bar F, and be provided with a guide attached to the under side of the table, as will be readily understood by the expert.

mechanic. The cross-bar F is pinned in the middle to the rod E, and attached at its extremities to the lifting-rods R R, which project through slotted openings α α in the table.

It is my design to make this cross-bar, F, sufficiently long to permit of the largest-sized person standing between the lifting-rods R R, which are pinned to the forked ends f f, and I have contemplated making a series of holes in these forked ends, so that the lifting-rods may be adjusted at different distances apart if desired, by altering the position of the pins g g.

In practice, it is necessary to adjust the height of the handles N N with respect to the table, and this may be accomplished either by a movable platform screwed into the table, and operating like the seat of a piano-stool, or by making the rods R R adjustable as to length, which is the mode I have adopted.

The lifting-rod R may be made in one piece, and have a thread cut on the lower part of it, so that it will screw into a swivel-nut secured in the fork of the cross-bar, or in two pieces or lengths, one partially tubular and the other solid, so that they may be attached to each other by means of a male and female screw. This latter form of construction is shown in fig. 1, where H is a sleeve, provided with a female thread for receiving the male thread on the upper part of the bar G.

I construct the handle-frames K in such a manner that the handles N may be taken out and others substituted, if desired.

This may be done either by making the bows K of steel, so that they can be sprung open sufficiently to let the handles N be removed, or by making them in two parts, and halving the lower ends of each part together, and cutting a thread thereon, so that they can be screwed into a sleeve or nut, as shown at z.

It will be understood that the inside of each arm of the bars K is slotted or countersunk to receive the ends of the handles N, as shown at m.

It is necessary to change the handles N to accommodate hands of different sizes, and the experienced mechanic will readily see various modes of construction by which that object can be attained, besides those already mentioned.

The weights W W are provided with a slot to accommodate the rod E, and are chamfered on the edges for the purpose of allowing the fingers to more easily seize and lift or remove them.

The operation of my apparatus is substantially similar to that heretofore used. The handles having been adjusted to the proper height above the table, the patient grasps them, and then stands erect, raising the weights which have been deposited upon the disk.

What I claim as my own invention, and desire to secure by Letters Patent, is—

A lifting-apparatus, constructed substantially as described, consisting of two adjustable vertical rods, projecting above a table on which the patient stands, connected with suitable mechanism beneath the table for carrying the weights used.

FRANK W. REILLY.
